REGROOVING TOOL

William A. Smith, Philadelphia, Pa.

Application July 13, 1942, Serial No. 450,717

6 Claims. (Cl. 77—58)

This invention relates to a tool for re-grooving annular grooves in a cylinder, and it consists in the constructions, arrangements, and combinations herein described and claimed.

In certain ignition timers now on the market, the breaker assembly is oscillatably supported by means of ball bearings operatively engaged in an annular groove formed upon the interior wall of the distributor body. The groove must be formed and maintained in proper concentric alignment with the operating shaft of the timer in order that the proper breaking period of the breaker assemblies will occur. Considerable wear of the groove occurs, as well as pitting of the metal defining the groove, which tends to produce an uneven oscillation of the breaker assembly, resulting in inefficient operation of the motor with which the timer is associated. It is therefore an object of the invention to provide a novel construction of cutter tool for properly reforming the groove of a timer housing.

It is also an object of the invention to provide a grooving tool in which the cutter blade may be readily adjusted from a point exteriorly of the timer housing when positioned therewithin.

It is a further object of the invention to provide a tool of the character described, in which an adapter is provided so constructed that the tool may be operatively connected upon the regular shaft of the timer, or upon an auxiliary shaft when it is desired to reform a groove of a fully dismantled distributor housing, such as may be carried in stock of repair and service garages.

The groove of the timer housing is not positioned at the same vertical height of the housing, the position varying according to whether the timer is employed for a four, six, eight or twelve cylinder engine, and in order that the same tool may be adapted to meet the various positions of the groove, it is an object of the invention to provide means whereby the cutter may be adjusted and secured for proper alignment of the groove.

Additional objects, advantages and features of invention will be apparent from the following description considered in conjunction with the accompanying drawings, wherein—

Figure 1 is a vertical section through a distributor housing showing my cutter installed,

Figure 2 is a fragmentary sectional view of the cutter illustrating its mounting upon a distributor shaft,

Figure 3 is a front elevation of the grooving tool,

Figure 4 is a sectional view illustrating installation of the tool in a stock distributor,

Figure 5 is a top plan view thereof,

Figure 6 is a fragmentary cross section illustrating an automatic means for retracting the cutter blade.

Attention is first called to Figure 1, wherein there is shown formally a conventional construction of distributor housing 10 comprising a base 11 portion 11 and cylindrical casing 12. A distributor shaft 13 is revolvably mounted in the base 12 as is customary, for support of a governor base 14 and governor weight 15. The governor base and weight are shown and referred to only because these are the only parts which may remain in the housing when employing the re-grooving tool. The weight 15 includes an upright sleeve 16 journaled on the distributor shaft, and normally carries the breaker cam 17 and rotor, the latter having been removed.

Reference is now made to Figure 2 of the drawings, for an understanding of the construction of the re-grooving tool, generally indicated at 18. An adapter 19 is employed, consisting of 25 an elongated metallic body having a cylindrical bore 20 extending concentrically from a bore 21 of greater diameter, the latter opening upon an end of the body. The bore 20 terminates inwardly of the opposite end of the body, and the body 30 is there formed with a nut member 22, for rotating the body by means of a suitable wrench.

Upon the adapter 19 a collar 23 is provided having a fit to permit a sliding fit, so that the collar may be moved vertically of the body to a required position, where it may be rigidly secured to the body by means of a screw 24. The collar 23 carries a frame 25, which in the present instance is shown as an L-shaped member providing a base 26 at right angles to the frame. The frame 25 is welded or otherwise secured to the collar and preferably at a point diametrically opposite the set screw 24. At the upper end of the frame 25, an internally threaded sleeve 27 is secured, and at a point spaced above the base 26, 45 a guide yoke 28 is fixed to the frame, the latter being angular in cross section, and receives a similarly shaped cam block 29.

The cam block 29 is adapted to be vertically adjusted, for a purpose presently to be explained, 50 and as shown, adjustment is obtained by means of a screw 30. The threaded shank 31 of the screw is engaged in the threaded sleeve 27, the lower end of which is of reduced diameter as at 32, the latter terminating in a head 33. The cam block 29 is in vertical alignment with the shank

31 and has a bore 34 of a size to rotatably receive the head 33 therewithin. A small set screw 35 is carried in the cam block adapted to enter the groove formed between the shank and the head 33. From the construction described, it will be readily seen that by rotating the screw 30 in a required direction, the cam block may be raised and lowered.

Upon the base 26, a cutter blade 36 is slidably mounted, guided and retained in proper position by means of a yoke 37 rigidly fixed to the base. In order to prevent rotation of the tool, the latter is of angular shape in cross section and the yoke is correspondingly formed. The cutter is of a length to extend a substantial distance beyond the end of the base 26, the rear end thereof being in contacting engagement with a cam face 38 formed at the lower end of the cam block. A set screw 39 carried by the yoke 37 and impinging upon the cutter, effects securement of the cutter in an adjusted position.

In the form described, the tool is to be rigidly locked with the distributor shaft 13 and sleeve 16 for rotation therewith, and this is accomplished in the provision of a set screw 40 engaged in a threaded aperture of the adapter 19, the screw extending into a cut-away portion 41 of the rotor support 42. The cut-away portion of the support ordinarily receives a tongue of the rotor so as to rotate therewith. In such cases where the collar 23 is adjusted to a low point on the adapter, the lower edge of the collar 23 is provided with a slot 43 which is brought into alignment with the screw 40 so as to permit access thereto.

In use of the device, the distributor casing to be regrooved is supported in a vise, generally indicated at 44, the shaft 13 being free for rotary movement. The tool is presented to the rotor support 42 so as to seat in the bore 21 and the screw 40 is then tightened. It is now necessary to align the cutting tool 36 with the groove 45 of the casing and this is accomplished by loosening the screw 24 and raising or lowering the collar 23 which carries the cutting blade, until the blade registers with the groove. The collar 23 may now be locked in position by tightening the screw 24. The set screw 39 having been previously loosened so that the blade 36 may slide upon the foot 26, it is only necessary to rotate the screw in a direction to cause the shank 31 to move in a downward direction, which will cause a similar movement to the cam block 29. The cam face 38 will thus be caused to exert a lateral pressure to the rear end of the cutter blade with consequent movement of the cutting edge of the blade into the groove. When proper adjustment of the blade has been attained, the set screw 39 is tightened to secure the blade. The tool and shaft is now rotated by the use of any suitable wrench applied to the nut 22 of the adapter and the tool 36 is caused to travel along and cut the groove 45.

It should be noted that all adjustments of the tool are exposed exteriorly of the distributor casing, permitting ready manipulation and that by reason of the camming action provided, a very accurate and fine adjustment of the cutting blade is made possible.

It should be understood that it is possible to remove the breaker cam 17 and its associated rotor support, in which event the bore 21 would be of such diameter as to not firmly seat the tool upon the shaft 13. Such a possibility is illustrated in Figure 2, and by reference to this fig-

ure it will be seen that the reduced portion of the shaft 13 is snugly engaged in the reduced bore 28, and thus the tool is properly supported.

It is necessary to adapt the tool for use on stock distributor housings in which there is no shaft upon which to mount the tool and in Figure 4, I have illustrated a means for effecting the re-grooving thereof. The tool employed is identical to that previously described, but in this instance, a shaft 46 is employed, of a diameter to fit the bore of the base 11. In this instance, the shaft is held against rotation by means of a vise 47, and the base of the housing rests upon a collar 48 of the shaft. The upper end of the shaft has a reduced shaft portion 49 of a diameter to be revolvably supported in the bore 20 of the adapter, but a portion of the shaft proper may also extend into the bore 21. The set screw 40 secures the adapter to the shaft 46. Adjustment of the cutter 36 is the same as before described, but the cutting operation is effected by rotating the housing.

It may be found desirable to provide a means for retracting the cutting tool after release of the set screw 39 and in Figure 6, I have illustrated such a means. The cutter 36 is mounted upon the foot 26 as before described, but upon one side thereof a pin 50 is provided and a tongue 51 is struck from the rear edge of the guide 37. A tension spring 52 is anchored between the pin and tongue and obviously, upon loosening of the set screw 39 the spring 52 will draw the cutter to a position outwardly of the groove of the distributor housing.

While I have shown and specifically described the cutting tool, this is by way of illustration only, and I consider as my own all such modifications in construction as fairly fall within the scope of the appended claims.

I claim:

1. A re-grooving tool for distributor housings comprising an adapter constructed for securement to the upper end of the distributor shaft, a collar on the adapter, a frame on the collar and carrying a cutter blade disposed at right angles to the wall of the housing of the distributor, and means movable in a plane parallel to the distributor shaft for effecting lateral movement of the cutter blade.

2. The structure of claim 1 in which said collar, frame and cutter blade are longitudinally movable as a unit along said adapter.

3. A cutting tool for cutting an annular groove in a cylindrical housing, an adapter having means for connection with a shaft concentric with the housing, a collar slidable on said adapter, means for securing the collar in an adjusted position, the collar including a frame extending parallel to the adapter, the frame having a right angular extension, a cutter blade on the extension and laterally movable, means movable in a plane parallel to the adapter and having operative engagement with the blade to impart lateral movement thereto, and means to lock said blade in adjusted positions.

4. A cutter tool for cutting an annular groove in a cylindrical housing, an adapter having means for connection with a shaft concentric with the housing, a collar slidable on said adapter, means for securing the collar in an adjusted position, the collar including a frame extending parallel to the adapter, the frame having a right angular extension, a guide on the frame, an internally threaded nut thereabove, a cam block reciprocable in the guide, a screw member

in the nut having its lower end revolvably mounted in the upper end of the cam block, a guide on the right angular extension, a cutter blade laterally movable therethrough upon camming engagement between the cam block and the rear end of the cutter blade, means to secure the blade in adjusted position, and means for rotating the adapter.

5. The structure of claim 4 in which means are provided for retracting the cutter blade upon loosening of said means for securing the blade in adjusted position.

10 6. A re-grooving tool for distributor housings

comprising an adapter constructed for securement to the upper end of a shaft concentric within the housing, said shaft having a reduced upper end, an adapter having aligned bores complementary to the shaft and reduced upper end, means for securing the adapter to the shaft, a collar on the adapter, a frame on the collar and carrying a cutter blade, disposed at right angles to the adapter and means movable in a plane parallel to the shaft for effecting lateral movement of the cutter blade.

WILLIAM A. SMITH.
